(57) **CLAIM**

The ornamental design for a hair curling appliance as shown and described.

DESCRIPTION

FIG. 1 is a bottom front perspective view of a first embodiment of an ornamental design for a hair curling appliance according to the present invention;

FIG. 2 is a right side elevational view of the hair curling appliance of FIG. 1;

FIG. 3 is a left side elevational view of the hair curling appliance of FIG. 1;

FIG. 4 is a front elevational view of the hair curling appliance of FIG. 1;

FIG. 5 is a rear elevational view of the hair curling appliance of FIG. 1;

FIG. 6 is a top plan view of the hair curling appliance of FIG. 1;

FIG. 7 is a bottom plan view of the hair curling appliance of FIG. 1;

FIG. 8 is a bottom front perspective view of a second embodiment of an ornamental design for a hair curling appliance according to the present invention;

FIG. 9 is a right side elevational view of the hair curling appliance of FIG. 8;

FIG. 10 is a left side elevational view of the hair curling appliance of FIG. 8;

FIG. 11 is a front elevational view of the hair curling appliance of FIG. 8;

FIG. 12 is a rear elevational view of the hair curling appliance of FIG. 8;

FIG. 13 is a top plan view of the hair curling appliance of FIG. 8; and,

FIG. 14 is a bottom plan view of the hair curling appliance of FIG. 8.

The broken lines in the drawings depict portions of the hair curling appliance, which form no part of the claimed design.
